CLAIM

The ornamental design for a toy water gun, as shown and described.

DESCRIPTION

FIG. 1 is a right side view of the toy water gun showing my new design. The left side view is a mirror image of the right side view.

FIG. 2 is a bottom perspective view of the toy water gun.

FIG. 3 is a front view of the toy water gun.

FIG. 4 is a rear view of the toy water gun.

FIG. 5 is a bottom view of the toy water gun; and,

FIG. 6 is a top view of the toy water gun.
